(57) **CLAIM**

The ornamental design for a support for a tabletop as shown and described.

DESCRIPTION

FIG. 1 is a perspective view of a first embodiment of a support for a tabletop illustrating my new design;

FIG. 2 is front elevation thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a perspective view of a second embodiment of a support for a tabletop illustrating my new design;

FIG. 8 is front elevation thereof;

FIG. 9 is a rear elevation view thereof;

FIG. 10 is a left elevation view thereof;

FIG. 11 is a right elevation view thereof;

FIG. 12 is a top plan view thereof;

FIG. 13 is a perspective view of a third embodiment of a support for a tabletop illustrating my new design;

FIG. 14 is a front elevation thereof;

FIG. 15 is a rear elevation view thereof;

FIG. 16 is a left elevation view thereof;

FIG. 17 is a right elevation view thereof; and,

FIG. 18 is a top plan view thereof.

The broken lines in the figures form no part of the claimed design. The surface shading is to indicate contours and not surface ornamentation or texture.
